UNITED STATES PATENT OFFICE

JOHN J. TATUM, OF BALTIMORE, MARYLAND

FREIGHT CAR TRUCK

Application filed August 28, 1929. Serial No. 388,991.

From service experience it has been established that it is desirable to use trucks under freight cars of flexible structure of the type shown in my application, Serial No. 285,899, so as to provide against binding of the truck in curves, thus insuring free movement of the trucks through curves which results in greater tonnage being drawn by the locomotive than is possible to be had with rigidly constructed trucks.

On account of this flexibility, there are, necessarily, loose connections of one part of the truck to another part, allowing for free movements of the parts. These conditions result in more or less wear where one part of the structure chafes against another, and it is one of the objects of my invention to provide for the correction of these conditions by using assembled parts that can be readily and cheaply renewed, thus eliminating the scrapping of the main structures, which results in longer life of the expensive parts of the truck.

A further object of my invention is to provide a removable wear plate assembled on the wearing face of the column post of the truck.

A further object is to provide removable wear plates for the bolsters.

A further object is to provide a wear plate for the rear end of the journal box.

A further object of my invention is to provide automatic lubrication in the journal box; and with these and other objects in view, my invention consists of the parts and combination of parts hereinafter pointed out.

In the drawings:

Figure 1 is a vertical sectional view through the side frame of a truck with integral journal box, including the wheel and journal.

Figure 2 is a detail top plan view of the side frame of a truck and journal box with the bolster in position.

Figure 3 is a side elevation of a side frame and journal box embodying my invention, associated parts of the truck being shown.

Figure 4 is a vertical sectional view of the truck side frame through the journal box.

Figure 5 is an end elevation of the rear splash pan.

Figure 6 is a transverse sectional view of the same.

Figure 7 is an end elevation of the front splash pan.

Figure 8 is a transverse sectional view of the same.

Figure 9 is a top plan view of the journal bearing showing the oil distributing grooves.

Figure 10 is a transverse sectional view of Figure 9.

Figure 11 is a detail sectional view.

The reference numeral 9 designates the side frame of a car truck, preferably of cast steel, having a journal box 10 cast integrally therewith. On the rear end of the journal box I provide a removable back plate 11 by means of the bolts 12, the heads of which are positioned in the annular groove 13 formed in said plate 11. Between the plate 11 and the journal box I secure a gasket 14. The plate 11 is, as shown, dish shape or pan shape, the flanges 15 offsetting it from the face of the box to provide a packing space or chamber and in this space or chamber I place a felt washer 16 which functions to prevent the oil from getting out of the journal box while the gasket 14 prevents leakage of oil at the joint between the plate 11 and the journal box. I provide a flat spring steel ring 17 around the felt washer 16 to retain the washer in proper position tight against the axle. The journal box is provided at its front end with a front plate 18, having a filling spout 19 closed by a plug 20, there being a gasket 21 between the plate 18 and the journal box to prevent oil leakage.

The purpose of the removable back 11 of the journal box is to provide for the renewal of the back when it is worn from coming in contact with the wheel hub 22, which renewal cost is much less than the cost would be of scrapping the entire journal box or the entire side frame of the truck should the journal box be cast integral with the side frame.

On the back of the journal 23, at the journal box pit, there is a pan shaped oil distributor 24 having corrugated sides 25. This distributor is placed on the journal box pit of the axle 26 by pressure so that as the axle rotates the oil distributor 24 rotates and oil

is carried up, in the corrugations 25, on top of the back of the journal bearing and journal bearing wedge, from which point the oil is distributed by grooves 27 to the ports 28, from which the oil is fed to the top of the journal. On the front of the journal a similar oil distributor 29 is attached and, as explained in connection with distributor 24, carries the oil up in the same way.

10 The ring 30 on the axle 23 is used only when this portion of the axle is smaller than standard A. R. A. dimensions enabling me to make the rear end oil distributor 24 for a standard axle,—the ring serving to take up 15 whatever difference that may be existing. This ring has a groove in which the inner edge of the disc 24 is sprung, whereby the disc is secured thereto.

10 The reference numeral 31 designates an overhanging edge or lip of the dust guard opening near the bottom of the box, the purpose of which is to prevent oil from swishing up to the dust guard. The lower dust guard wall is bevelled as at 32 so that when oil 25 swishes against the dust guard it will freely run back into the bottom of the box. This method of lubrication eliminates the use of saturated waste in the bottom of the journal box and provides for the lubrication of the 20 journal with free oil.

10 The side frame column post 33 is provided with a removable wear plate 34 riveted to the column post, and can be readily removed and renewed by the removal and replacement 15 of the rivets. The bolster 35 is provided with a removable wear plate 36 which is riveted to the side of the bolster that chafes against the wear plate 34 on the column post.

10 At the bottom of the side frame I provide an elongated slot 37 in which is placed the rod 38 which extends from side frame to side frame on the truck. This rod eliminates the use of the conventional spring plank formerly used across the truck, and reduces the 15 weight and cost of the truck. This is accomplished by arranging the floor space on the top of the lower section of the truck side frame between the two column posts of sufficient size to provide for the sealing of the helical springs placed under the ends of the truck bolster which carry the load of the car. The tie rod 38 provides for flexibility in the truck being positioned in the elongated slot 37, and eliminates the rigidity formerly present in the use of the conventional spring plank.

10 The inner portion of the top edge of the journal bearing flange is tapered as at 33' providing an intake for the oil from the oil distributor on the axle to the top of the journal.

10 In Figure 11 I have shown the spring seat floor 34 surrounded by an upward projecting flange 35, from its rear and forward edges to prevent displacement of the springs from the

force caused by the lateral movement of the bolster between the column post.

What I claim is:

1. In combination, in a car truck, a journal box, a journal in said box, a disc secured to said journal having a bodily crimped annular flange, said crimps of the flange forming corrugations to pick up oil in the bottom of the box and convey it to the top of the box and means to convey the oil to the top of the journal.

2. In combination, in a car truck, a journal box, a journal in said box, a sheet metal disc secured at the rear of the journal within said box and flanged toward the front of the box, and a sheet metal disc secured to the front end of the journal and flanged toward the rear of the box, said discs rotating through oil in the bottom of the box and having their flanges bodily crimped to provide undulating surfaces forming pockets to pick up oil and convey it to the top of the box.

3. In a bearing, a journal box, a journal arranged therein, a journal bearing located on the top of the journal and provided with oil distributing channels extending through its top and sides, and rotating discs carried by the journal and having crimped flanges forming corrugations for raising oil from the bottom of the box to said channels.

4. In a car journal, a journal box having an oil reservoir at its base, a journal extending into the box, an annular oil elevating member surrounding the journal and having an edge portion spaced from an adjacent part of the journal, and a grooved distance-take-up ring surrounding the journal and disposed between the same and said edge portion of the oil elevating member, said edge portion of the oil elevating member being secured in said groove.

5. In a car journal, a journal box having an oil reservoir at its base, a journal extending into the journal box, a journal bearing at the top of the box having oil receiving channels at the ends thereof and oil feed ports extending from said channels to supply oil to the journal, and discs at the ends of the journal having annular flanges overhanging the ends of the bearing and dipping into the oil in the reservoir and crimped to provide undulating pockets therein to convey oil from the reservoir to the said oil receiving channels in the bearing.

In testimony whereof I affix my signature.

JOHN J. TATUM.
